UNITED STATES PATENT OFFICE

2,383,984

ZERO PHASE SHIFT SELECTIVE AMPLIFIER

Gilbert E. Oberweiser, Cedar Rapids, Iowa, assignor to Collins Radio Company, Cedar Rapids, Iowa, a corporation of Iowa

Application October 30, 1943, Serial No. 508,334

12 Claims. (Cl. 179—171)

My invention relates broadly to selective electrical amplifier systems and more particularly to a circuit arrangement for maintaining the phase shift of amplified energy throughout the transmission band at substantially zero.

One of the objects of my invention is to provide an improved circuit arrangement for a selective amplifier system in which means are included for maintaining the phase shift of the amplified signalling energy through the transmission band at substantially zero.

Another object of my invention is to provide a circuit arrangement for a selective amplifier system in a transmission channel in which phase shift of the transmitted energy in the transmission channel throughout any given frequency band is eliminated.

Still another object of my invention is to provide a novel arrangement of coupled circuits for a transmission channel designed to prevent phase shift of the transmitted energy in the transmission channel.

Other and further objects of my invention reside in the arrangement of parallel connected networks associated with the transmission channel of a transmission system for eliminating phase shift through the transmission system as set forth more fully in the specification hereinafter followed by reference to the accompanying drawings, in which:

Figure 1 diagrammatically illustrates a transmission channel including the novel arrangement of my invention for maintaining phase shift through the transmission channel at practically zero; Fig. 2 illustrates the phase characteristics of two of the parallel networks employed in association with the transmission channel in accordance with my invention; Fig. 3 illustrates the attenuation characteristic of one portion of the transmission channel; and Fig. 4 shows the characteristics of the selective amplifier system in the transmission channel equipped with the protective circuits of my invention and illustrating the operation of the transmission channel with practically no phase shift throughout the transmission band.

The amplifier consists of a resistance coupled main channel and two feedback circuits each consisting of two parallel-T networks connected in tandem as shown in Fig. 1. The amplifier in the main channel is provided with input terminals 1 connected to isolation tube 2 which connects to the amplifier stage including tube 3 through resistance coupled circuit 4. The output circuit of amplifier stage 3 connects to the input circuit of

isolation tube 5 through coupling resistors 6—7 and condenser 8. The output circuit of isolation tube 5 connects through resistance network 9 to the input circuit of the amplifier stage including tube 10. The output circuit of tube 10 includes coupling resistor 11 connected through condenser 12 with output terminals 14 of the selective amplifier. The main channel of the transmission system thus includes the combination of isolation tube 2 and amplifier tube 3 represented as a unit within dotted lines 15 and isolation tube 5 and amplifier tube 10 represented as a second unit within dotted line 16. The protective circuits for each of these units have been indicated generally within dotted lines 17 and 18 respectively. I have designated the main channel section 15 and the protective section 17 as unit A while the main channel section 16 and its associated protective section 18 is designated unit B. I have designated section 17 as "feedback circuit A," all the elements of which are adjusted to the lower band limit of the frequency range of the associated main channel section 15. The section 18 has been designated as "feedback circuit B," the elements of which are adjusted to the upper band limit of the frequency range of the main channel section 16. Each of the protective circuits includes a feedback loop that I have schematically represented at 19 and 20 to illustrate the action which takes place in both units A and B. The input path to the protective circuit extends from the output circuit of the main amplifier stage 3 to the two parallel-T networks represented at 21 and 22 connected in tandem. Network 21 includes capacity elements 23 and 24 and resistance element 25. Network 22 comprises resistance elements 26 and 27 and capacity element 28. These parallel-T connected networks connect to the input circuit of electron tube 29, the output circuit of which is coupled to resistance coupled system to the input circuit of tube 31. The output circuit of tube 31 connects to the two parallel-T networks in tandem illustrated at 32 and 33. Network 32 includes capacity elements 34 and 35 and resistance element 36. Network 33 includes resistance elements 37 and 38 and capacity element 39. The two parallel-T networks 32, 33 connect to the input circuit of isolation tube 40, the output circuit of which returns to the input circuit of amplifier stage 3 of the main channel transmission system. The elements in the protective circuit of section 17 are adjusted to the frequency F_1 which designates the lower band limit of the selective frequency range of the transmission channel.

The feedback circuit B constituting protective section 18 contains parts which are arranged in a symmetrical manner to the parts explained in connection with feedback circuit A and to designate the similarity and identity of the parts I have represented corresponding elements by the same reference characters which are primed in section 18 representing the correspondingly numbered parts in section 17. The elements of the feedback circuit B are adjusted to the upper band limit of the frequency range of the main channel section 16. The protective circuit of section 18 connects between the output circuit of tube 10 and the input circuit of tube 10 as shown in a manner similar to the arrangement in unit A.

Since the main channel has no tuned circuits, there will be practically no phase shift through this channel throughout any given frequency band. The phase characteristics of two parallel-T networks in tandem (each tuned to 455 kc.) are shown in Fig. 2. Thus, through any band width up to approximately 30 kc., the phase shift through the feedback circuit is practically constant at 180°. The net phase shift through unit A (Fig. 1) is then zero for all relatively narrow frequency bands.

The attenuation characteristics of unit A are shown in Fig. 3. These are approximately squared functions of frequency deviation, due to the use of the two parallel-T networks in tandem. Staggering two such curves the proper amount and multiplying the ordinates result in flat top band pass curves shown in Fig. 4. Unit B serves as the second zero phase shift unit with transmission characteristics properly staggered from those of unit A.

The net characteristics of the whole amplifier, then, results in transmission characteristics as shown in Fig. 4, with practically no phase shift throughout this transmission band.

The band width of the amplifier is controlled by the two frequencies (F₁ and F₂, Fig. 1) at which the two sets of T networks are nullled, and by the total gain around each feedback circuit which gives the proper slopes to each of the individual attenuation curves so that when the two are multiplied a flat-top curve will result. A narrow band-pass results in steeper attenuation curves, as shown in Fig. 4. This selectivity, or relative gain, is determined by the expression,

$$\mu_0 = \frac{\mu}{1 - \mu a}$$

μ is the amplifier gain taken around the total loop circuit, with no attenuation in either parallel-T network. a is the total attenuation

input
output

of the two parallel-T networks. μ_0 is a relative figure of gain.

If there were no gain in the feedback circuit (all gain confined to the main channel), μ_0 would be the gain of the amplifier. If the total loop gain is split, however, the amplifier gain will be less than μ_0 . This gives flexibility inasmuch as the selectivity (μ_0 factor) is determined by the total gain around the loop circuit, and the amplifier gain can be controlled by using any portion of this gain in the main channel.

A proper number of tubes in the loop circuit is necessary to obtain proper degenerative phase relations between the feedback and input circuits and it will be understood that the circuits illustrated are merely for the purpose of ex-

plaining my invention and are not in any way indicative of the number of tubes employed.

The tandem pairs of parallel-T networks produce a 180° phase shift through themselves as shown in Fig. 2, since each individual parallel-T network has a phase shift of plus 90° on the high frequency side of null and minus 90° on the low side, these phase shifts being practically constant as the frequency approaches the null point. 10 Two of these configurations in tandem, then, multiply the phase angle of each network by two which makes the resultant phase shift through the whole 180° on either side of the null frequency.

15 This apparent discontinuity at the null frequency will be of no consequence in steady-state applications, since in this case, a plus 180° phase shift and a minus 180° shift result in the same vector position. Furthermore, at the null frequency, the feedback vector is theoretically zero. Thus the phase shift of the amplifier at this point is not influenced by the feedback circuit.

It follows from the foregoing that the null frequency of each pair must be very nearly identical. If this condition is not satisfied the phase shift outside the two individual null frequencies will still be 180° but the phase shift between these two frequencies will be zero. This will destroy the zero phase shift characteristics of the amplifier, may cause oscillations, and will make the band pass characteristics of each unit (A and B, Fig. 1) have double peaks which would destroy the flat-top pass characteristics shown in Fig. 4.

30 While I have described my invention in one of its preferred embodiments, I desire that it be understood that modifications may be made and no limitations upon my invention are intended other than may be imposed by the scope of the appended claims.

40 What I claim as new and desire to secure by Letters Patent of the United States is as follows:

1. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said 45 amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero.

2. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said 55 amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero.

3. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said 60 amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero.

4. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said 65 amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero.

5. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said 70 amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero.

6. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said 75 amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero.

the output circuit of said last mentioned amplifier tube to the transmission network, and feedback loop circuits comprising coupled electron tubes connected between the output circuit of each amplifier tube and the input circuits of the said amplifier tube for maintaining the phase shift of amplified energy throughout the transmission band at substantially zero.

3. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits comprising coupled electron tubes and an isolation tube, connected between the output circuit of each amplifier tube and the input circuit of the said amplifier tube for maintaining the phase shift of amplified energy throughout the transmission band at substantially zero.

4. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits comprising coupled electron tubes with the output of the last of said coupled tubes connected to an isolation tube and connected between the output circuit of each amplifier tube and the input circuit of the said amplifier tube for maintaining the phase shift of amplified energy throughout the transmission band at substantially zero.

5. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits comprising coupled electron tubes with a network connected in the input circuit thereto and an isolation tube connected in the output thereof and connected between the output circuit of each amplifier tube and the input circuit of the said amplifier tube for maintaining the phase shift of amplified energy

throughout the transmission band at substantially zero.

5 6. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another 10 of said amplifier tubes, circuit connections leading from the output circuit of said last mentioned amplifier tube to the transmission network, and feed back loop circuits comprising coupled 15 electron tubes with a pair of parallel-T networks connected in the input circuit thereof and an isolation tube connected in the output circuit thereof and connected between the output circuit of each amplifier tube and the input circuit of the said amplifier tube for maintaining the phase 20 shift of amplified energy throughout the transmission band at substantially zero. 25

7. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits connected between the output circuit of each amplifier tube and the input circuit of the said amplifier tube for maintaining the phase shift of amplified energy throughout the transmission band at substantially zero, one of said feedback loop circuits being tuned to the lower frequency band limit and the other of said loop circuits being tuned to the upper frequency band limit of the transmission system.

5. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling 55 the output circuit of said amplifier tube with the input circuit of said last mentioned isolation tube, connections between the output circuit of said last mentioned isolation tube and another of said 60 amplifier tubes, circuit connections leading from the output circuit of said last mentioned amplifier tube to the transmission network, and feedback loop circuits comprising coupled electron tubes connected between the output circuit of each amplifier tube and the input circuit of the 65 said amplifier tube for maintaining the phase shift of amplified energy throughout the transmission band at substantially zero, and one of said feedback loop circuits being tuned to the 70 lower frequency band limit and the other of said feedback loop circuits being tuned to the upper 75

frequency band limit of the transmission system.

9. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits comprising coupled electron tubes and an isolation tube connected between the output circuit of each amplifier tube and the input circuit of the said amplifier tube for maintaining the phase shift of amplified energy throughout the transmission band at substantially zero, one of said feedback loop circuits being tuned to the lower frequency band limit and the other of said feedback loop circuits being tuned to the upper frequency band limit of the transmission system,

10. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits comprising coupled electron tubes with the output of the last of said coupled tubes connected to an isolation tube and connected between the output circuit of each amplifier tube and the input circuit of the said amplifier tube for maintaining the phase shift of amplified energy throughout the transmission band at substantially zero, one of said feedback loop circuits being tuned to the lower frequency band limit and the other of said loops circuits being tuned to the upper frequency band limit of the transmission system.

11. In a signal transmission system, a multi-

stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, and feedback loop circuits comprising coupled electron tubes with a network connected in the input circuit thereto and an isolation tube connected in the output thereof and connected between the output circuit of each amplifier tube and the input circuit of the said amplifier tube for maintaining the phase shift of amplified energy throughout the transmission band at substantially zero, one of said feedback loop circuits being tuned to the lower frequency band limit and the other of said feedback loop circuits being tuned to the upper frequency band limit of the transmission system.

12. In a signal transmission system, a multi-stage electron tube amplifier comprising a multiple number of tubes each including input and output circuits, an isolation tube having its input circuit connected with the transmission channel and its output circuit connected with one of said amplifier tubes, another isolation tube having input and output circuits, means for coupling the output circuit of said amplifier tube with the input circuit of said last mentioned isolation tube, connections between the output circuit of said last mentioned isolation tube and another of said amplifier tubes, circuit connections leading from the output circuit of said last mentioned amplifier tube to the transmission network, feedback loop circuits comprising coupled electron tubes with a pair of parallel-T networks connected in the input circuit thereof and an isolation tube connected between the output circuit of each amplifier tube and the input circuit of the said amplifier tube for maintaining the phase shift of amplified energy throughout the transmission band at substantially zero, one of said feedback loop circuits being tuned to the lower frequency band limit and the other of said loop circuits being tuned to the upper frequency band limit of the transmission system.

GILBERT E. OBERWEISER.
